UNITED STATES PATENT OFFICE.

ALEXANDER JAEGER, OF PHILADELPHIA, PENNSYLVANIA.

VENDING-MACHINE.

No. 898,371.

Specification of Letters Patent.

Patented Sept. 8, 1908.

Application filed September 6, 1905. Serial No. 277,220.

To all whom it may concern:

Be it known that I, ALEXANDER JAEGER, a citizen of the United States, residing in Philadelphia, Pennsylvania, have invented 5 certain Improvements in Vending-Machines, of which the following is a specification.

My invention relates to coin actuated vending apparatus of the type shown and described in the patent of Otto Jaeger, dated 10 August 2, 1904, and numbered 766,445.

The object of my invention is to facilitate the discharge of the articles to be vended and to provide a construction that will take care of vendible units whose general dimensions 15 are the same, but which may vary in size a slight degree and hence are not readily vended in structures wherein the feeding, discharge and actuating mechanisms are based upon certain proportional dimensions.

20 My invention is fully shown in the accompanying drawing, in which:

Figure 1, is a sectional elevation of the vending structure made in accordance with my invention, showing it in the inactive position; Fig. 2, is a similar view, showing the apparatus in position to eject the vendible units; Fig. 3, is a front elevation of the carrier for the vendible units, and Fig. 4, is a modification of the coin actuating or controlling means.

The general form of vending apparatus to which my improvements have been applied is shown in the patent above referred to, and hence it will be unnecessary to describe the 35 same at length herein.

The articles 1, to be vended, are carried by a platform 2 suspended by bands or cords 3 depending from wheels or drums 4 on a shaft 5, which shaft is carried at the top of a suitable frame 6. The sides of the frame are slotted at 7 for the passage of end projections 8 of the platform 2, to which projections said bands 3 are connected. The shaft 5 carries a coiled band spring 9 which is wound by the 40 depression of the platform 2, said spring having a constant tendency to raise said platform.

Journalized in the frame 6 and disposed below the shaft 5 is a shaft 10 carrying a pair of 50 escapement wheels 11 held against turning by means of a pawl 12; the upper vendible unit being in engagement with said escapement wheels. The pawl 12 is mounted on a rock-shaft 13 and is provided with an exten-

sion 14 which serves to prevent the escapement wheels moving more than one tooth or a quarter revolution at a time.

A coin chute 15 is provided, having the usual means for ejecting improper coins or slugs, and the lower end of this chute is beveled at 17. Extending from the shaft 13 is an arm 18 having an angular portion 19 lying against the beveled lower end of the coin chute and held in such position by means of a spring 20. Upon passing a coin into said chute it drops to the lower end, and in leaving the chute it pushes the projection 19 out of the way. This causes the pawl 12 to release the ratchet wheel, whereupon the spring 9, whose constant tendency is to raise 65 the platform 2 carrying the vendible units, exerts its force and causes the upper vendible unit to press against the rounded back of the teeth of the escapement wheels in engagement with said units, causing such 70 wheel to turn and permitting the succeeding teeth of the wheels to kick the uppermost unit from the pile. Further movement of these wheels is prevented by the extension 14 of the pawl 12 and the balance of the vendible units, and hence when the uppermost unit 75 has been discharged, the escapement wheels will come to a point of rest against the succeeding vendible unit.

In loading the machine, the articles are 80 placed successively on the platform 2, which is depressed to permit such action and in order that it may be satisfactorily held during such loading, I provide the shaft 4 with a ratchet wheel 25 engaged by a pawl 26 which 85 is weighted so as to normally hold said shaft against movement during this operation. This pawl has a lower extension 27 pivoted at 90 28, with a side projection 29, and when the machine has been filled, the uppermost unit 95 is in position to engage this projection and keep the pawl 26 away from its ratchet wheel 25 and thereby permit the successive ejection of the vendible units. The extension 27 is guided by a pin 30 extending into 100 the slot 7.

Fig. 4, illustrates a modified form of coin chute 15^a and escapement mechanism. The rock-shaft 13^a carries a pawl 12^a having an extension 14^a, and a spring 20^a coiled around 105 said rock-shaft serves to keep the pawl in the proper engaging position. A platform 31 pivoted at 32 is provided to receive the coin,

and a rod 32 connects said platform with the rock-shaft so that the latter may be turned by the dropping of the coin on said platform.

In my improved construction no part of 5 the apparatus depends upon the proportional dimensions of the articles to be vended, inasmuch as the operation of the mechanism, after it has been released or actuated by a coin, depends simply upon the force exerted 10 by the coiled spring, which tends to raise the vendible units against the escapement wheels.

Having thus described my invention, I claim and desire to secure by Letters Patent:

1. The combination, in a vending apparatus, of a frame or guide, a platform for the articles to be vended, a shaft, drums at the end of said shaft, bands arranged to be wound on said drums and attached at their opposite ends to said platform, a coiled 20 spring on said shaft for turning the same to lift the platform, said spring being wound when the platform is depressed for the reception of the vendible units, escapement means comprising a toothed wheel and 25 a pawl normally in engagement therewith for co-action with said lifting means, said wheel having rounded teeth for engagement with the uppermost vendible unit, an escapement lever carrying the pawl engaging 30 said wheel and adapted to be swung to one side to release the same, means for swinging said lever back to its initial position thereby causing said projection to engage another tooth of the wheel while the vendible unit is 35 being delivered, a ratchet on the spring shaft,

a pawl therefor, and an arm carried by the pawl for controlling said ratchet, said arm lying in the path of the vendible units and engaged by the same so as to hold the said pawl out of engagement.

2. In a vending apparatus, the combination of a platform for the vendible units, a shaft from which said platform is suspended, means tending to raise said platform, a ratchet wheel carried by said shaft, a pawl for 40 engagement with said ratchet wheel, and an extension carried by said pawl and lying in the path of the vendible units whereby the engagement of said extension by the vendible units holds the pawl normally out of engagement with the ratchet wheel.

3. In a vending apparatus, the combination of a platform for the vendible units, a shaft from which said platform is suspended, a torsion spring carried by said shaft and 45 tending to raise said platform, a ratchet wheel carried by said shaft, a pawl for engagement with said ratchet wheel, and an extension carried by said pawl and lying in the path of the vendible units whereby the engagement of said extension by the vendible units holds the pawl normally out of engagement with the ratchet wheel.

In testimony whereof, I have signed my name to this specification, in the presence of 55 two subscribing witnesses.

ALEXANDER JAEGER.
